Des. 239,707
Patented Apr. 27, 1976

239,707

VEHICLE HOISTING TRAILER

Samuel Grimaldo, 776 W. Sandoval,
Thousand Oaks, Calif. 91360

Filed Jan. 6, 1975, Ser. No. 538,552

Term of patent 14 years

Int. Cl. D12—05, 10

U.S. Cl. D12—56

FIG. 1

FIG. 2

FIG. 3

FIG. 4

FIG. 5

FIG. 1 is a perspective view of a vehicle hoisting trailer, showing my new design;

FIG. 2 is a side elevational view thereof;

FIG. 3 is a top plan view thereof;

FIG. 4 is a front elevational view thereof; and

FIG. 5 is a rear elevational view thereof.

I claim:

The ornamental design for a vehicle hoisting trailer, substantially as shown.
